UNITED STATES PATENT OFFICE

2,490,928

GUN TURRET AND SHIELD THEREFOR

Ernest W. Stacey, Beverly, Mass., assignor to
United Shoe Machinery Corporation, Flemington, N. J., a corporation of New Jersey

Application April 2, 1946, Serial No. 659,054

2 Claims. (Cl. 89—36)

1

This invention relates to improvements in a gun turret and more particularly to a closure for the port in a tank turret through which a gun extends.

The usual elongated port in a tank turret, which permits the gun to be elevated through a considerable angle, is commonly closed inside the turret by the rotor on which the gun is mounted for purposes of moving it in elevation. An additional outer closure for the port may be provided by the use of a shield which closely fits the gun barrel and covers at least a part of the port at the outside of the turret. Such a shield may be effective on guns which are not intended to have a wide range of elevating movement. However, a shield of such length as would cover one end of the port for an antiaircraft gun when the gun is at the other end of the port would interfere with adjacent parts of the turret or tank body soon after the gun is moved away from its above-mentioned position. Accordingly, the shield is commonly made so short in a mount of this type, particularly below the gun, that a substantial area of the lower part of the port and rotor lacks any outer protection when the gun is pointed at the higher elevations.

Moreover, the lower parts of the rotor and shield usually slope downwardly toward the rear of the tank, and the adjacent outer surfaces of the turret or tank body below the gun are usually sloped downwardly toward the front of the tank to permit the gun to be depressed. This relation of the rotor or shield and the turret results in the formation of a re-entrant or pocket-like space below the gun when the latter is at any substantial elevation.

These conditions increase the vulnerability of the tank at the port primarily because a shell which hits the tank within the pocket is not deflected away from the turret. If the shell strikes the rotor the latter may be immobilized by small mounds of metal from the shell which adhere to it or become jammed in the gap between it and the turret. In addition, the blast from the explosion is confined sufficiently to abet its spouting, with shell fragments, into the tank through the clearance space between the turret and the rotor.

In view of the foregoing, an object of the invention is to provide an improved port closure for a gun turret, which, without impairing the freedom of movement of the gun, presents an effective shell deflecting surface, below as well as above the gun.

To this end, the illustrated port closure com-

5 prises with a shield for closing one segment of the port which includes the gun, a flap contiguous to the shield for closing the remaining segment of the port, the flap being arranged to swing forwardly into an upwardly inclined position as the gun is lowered in elevation. For substantially all positions of the gun in elevation both the shield and the flap slope upwardly to the rear of the turret whereby an effective deflecting action is afforded by the entire closure.

15 As another feature of the invention, the above-mentioned flap is hinged to the shield immediately below the gun and is swung by its engagement with the outside of the turret as the shield rises and falls. The flap is thus adapted and arranged to bridge the space below the gun, which formerly was a dangerous pocket, and yet to permit the gun to be moved freely into its lowest possible position of depression.

20 These and other features of the invention will now be further described in the following specification by reference to the accompanying drawings and will be defined in the claims.

In the drawings,

Fig. 1 is a view in perspective of an illustrative tank turret embodying the invention; and

Fig. 2 is a sectional elevation of the structure shown in Fig. 1, the section being taken along a vertical plane extending fore and aft with respect to the turret and at one side of the gun.

25 Certain usual features of tank construction will first be described with reference to the drawings which show an illustrative embodiment of the invention in a closure for a typical gun port of a tank turret.

30 On the upper part of the body 10 of the tank is rotatably mounted a turret 12 which is fitted with a cannon 14 and a machine gun 16. The cannon and gun are carried by a rotor 18 arranged to be swung about a horizontal axis at 19, the turret being cut away to provide a port 20 through which the cannon and gun extend and swing without interfering with the turret as their elevation is changed. The rotor 18 closely fits the inner sides of the turret bordering on the port 20 and is itself an element of the tank's armor since it acts as an inner closure for the port. The port 20 is formed concentrically with the axis of the rotor 18 and is of such extent as to permit the cannon 14 and gun 16 to be moved in elevation from a position of depression, a few degrees below the horizontal, to an elevation of about 60°. A sloping front 22 on the turret further makes available the necessary space for depressing the cannon and gun.

The space bounded by the sides of the port 20 and the rotor 18, as well as that between the rotor and the front 22 below the cannon and gun, tend to trap the blast from an exploding shell, particularly when the cannon and gun are at a low elevation or depressed. Moreover, the rotor 18 may be immobilized by small mounds of metal from a projectile which may adhere to the rotor or become jammed in the joint between the rotor and the turret 12. Another hazard results from the spouting effect of the blast or of metal particles—usually very hot or even molten—through the clearance space between the rotor and the turret.

In order to minimize or obviate these occurrences, the illustrated port closure comprises additional elements of armor, namely, an outer shield 24 and a flap 26 which are mounted and arranged, as will presently be described, to deflect missiles striking the closure and to provide with the rotor 18 a zigzag clearance space between the turret and the moving parts of the closure for impeding the entry of a blast or of metal particles into the tank.

The shield 24 is connected to the rotor 18 by a short column 27 which is cast integral with the shield and rotor and also is bored closely to receive the cannon 14 and gun 16. At times the cannon and gun will be referred to herein for convenience simply as the "gun," this term being intended to designate either or both pieces of ordnance as illustrated herein, or any other similar piece. The lower edge of the shield is disposed just below the gun and the remainder of the shield extends upwardly concentrically with the axis of the rotor 18. The shield 24 thus covers the upper segment of the port 20 including that area contiguous to the gun. The lateral edges of the shield are turned inwardly to form lips 28 which overlie ribs 30 extending radially outwardly from the turret along its margins at each side of the port 20.

A knuckle 32 which extends outwardly from the lower edge of the shield 24 closely fits between two other similar knuckles 33 formed along the upper edge of the flap 26. A hinge pin 34 passes through all the knuckles thereby providing a pivotal mounting for the flap on the shield. The flap also is shaped with a curvature like that of the shield and has lips 36, similar to the lips 28 on the shield, which are adapted to overlie the ribs 30 when the gun is elevated.

It is now evident that the flap 26 protects the segment of the port 20 below the gun, even against fire of low trajectory, when the gun is elevated to a position as indicated by broken lines in Fig. 2. Accordingly, it is unlikely that the rotor could be immobilized by fire directed below the gun while it is elevated, since the flap deflects projectiles away from the pocket mentioned above between the rotor and the turret. Moreover, a blast and flying fragments are deterred from entering the turret through the clearance space by its zigzag course between the lips 28, 36, and the ribs 30, and thence between

the rotor 18 and the turret 12, since this passage changes direction by at least four angular turns, two of which are at a right angle.

As the gun is lowered in elevation from its higher position shown in Fig. 2, the lower edge of the flap rides downwardly and forwardly over the front 22 of the turret and the tank body. This action of the flap results in its being swung upwardly relatively to the gun whereby an effective deflecting action against direct fire is obtained at a location where the tank would be vulnerable without the flap, particularly at low gun elevations.

With the cannon 14 and machine gun 16 mounted somewhat above the axis of the rotor, as they are herein illustrated, the shield always slopes upwardly to the rear regardless of the elevation of the cannon and gun. Similarly, throughout a substantial range of elevation the entire flap has a definite upward slope to the rear. Accordingly, the whole closure effectively deflects fire away from the port and the turret under all conditions of elevation and opposing fire.

Having thus described my invention, what I claim as new and desire to secure by Letters Patent of the United States is:

1. In a gun mount for a tank, a turret having an arcuate section provided with an elongated port, said arcuate section also having ribs extending radially therefrom one at each side of said port, a rotor for supporting a gun arranged to project through the port, said rotor being mounted to swing concentrically with said arcuate section in proximity to the inner surface thereof thereby to provide an inner closure for the port, and a shield mounted on said rotor concentrically with said arcuate section outside of said turret, said shield having inwardly turned lips arranged to overlap the ribs of said arcuate section whereby a zig-zag clearance space is formed between said arcuate section, shield and rotor.

2. In combination, a turret in which a gun is mounted for rotation, said turret having an elongated port and ribs extending outwardly from and along the margins of the turret bordering on each side of the port, and a closure for the port comprising a shield and a flap hinged to said shield, said shield and flap being arranged to overlie said ribs at each side of said port and having lips disposed outside of said ribs, said lips being arranged to extend inwardly toward and into proximity to the turret.

ERNEST W. STACEY.
